UNITED STATES PATENT OFFICE.

CLARENCE B. BURBRIDGE, OF GARDNER, KANSAS, ASSIGNOR TO THE PLAYGROUND EQUIPMENT CORPORATION, OF KANSAS CITY, MISSOURI, A CORPORATION OF MISSOURI.

MERRY-GO-ROUND.

Application filed July 26, 1926, Serial No. 124,934. Renewed April 30, 1928.

My invention relates to improvements in merry go rounds.

It relates particularly to a type in which the riders provide the propelling power for 5 the machine.

One of the objects of my invention is to provide a merry go round of the kind described with novel propelling mechanism by which the riders obtain the exercise and 10 enjoy sensations similar to that to be had in rowing a boat.

A further object of my invention is the provision of novel means for rotatably supporting the device which carries seats for 15 the riders, and which permits of the quick and easy assembling or disassembling of the parts.

My invention provides further a novel construction which is simple, cheap, durable, 20 strong, not liable to get out of order, and which is safe and efficient in its operation.

The novel features of my invention are hereinafter fully described and claimed.

In the accompanying drawings which illustrate my invention,

Fig. 1 is a plan view of the preferred form of my invention, partly broken away.

Fig. 2 is a side elevation of the same, the housings for the outer gears being shown in 30 dotted lines.

Fig. 3 is an enlarged, central vertical sectional view of the same, partly broken away, and parts omitted.

Fig. 4 is a top view, enlarged, of one of 35 the operating levers, partly broken away, and parts connected therewith.

Fig. 5 is a vertical section on the line 5-5 of Fig. 6, showing a modification of my propelling mechanism.

Fig. 6 is a plan view of the same, parts 40 being broken away.

Fig. 7 is an enlarged section on the line 7-7 of Fig. 5.

Fig. 8 is an enlarged section on the line 45 8-8 of Fig. 5.

Similar reference characters designate similar parts in the different views.

My invention provides a rotary seat carrying device, comprising, preferably, two horizontal crossed beams 1 and 2, which are 50 adapted to serve as sweeps for supporting seats 3 at the outer ends respectively of said beams, Figs. 1 and 2.

Extending vertically through the beams 1 and 2 at their place of intersection is a bearing tube 4 provided adjacent to its lower end with a peripheral annular flange 5 which bears against the under side of the lower beam 2. Fitted on the tube 4 and resting against the upper side of the top beam 1 is 55 a collar 6. Vertical bolts 7 extend through the beams 1 and 2 and through the flange 5 and collar 6, whereby the beams are firmly fastened together, and are easily assembled and disassembled, see Fig. 3.

Extending upwardly into the tube 4 is a vertical spindle 8, similar to that used on an automobile, and having a peripheral flange 9 upon which run bearing rollers, such as balls 10, which are mounted in a ball 70 race provided in the lower end of the bearing tube 4, and which support the latter.

The inner side of the tube 4 has an annular race in which are mounted balls 11 which run upon the periphery of the spindle 8, and against a bearing collar 12 removably mounted on the threaded upper end of the spindle 8 and held in place by a nut 13 on said spindle. The upper end of the tube 4 is threaded and has fitted thereon a removable hub cap 14.

For supporting the spindle 8, there is provided a cap 15 which is mounted on the upper end of a vertical pipe 16, which is mounted at its lower portion in the ground, 85 and which has in it a filling, such as concrete 17 into which extends a stem 18, with which the lower portion of the spindle 8 is provided, said stem being removably mounted in the concrete and in a vertical central 90 hole in the cap 15. The latter may have threaded connection with the pipe 16, Fig. 3.

I will first describe the preferred embodiment of my invention shown in Figs. 1 to 4.

In order that the riders may propel the seat support formed by the fastened together beams 1 and 2, there is provided concentrically on the pipe 16 a fixed bevel gear wheel 19 in which mesh four bevel pinions 20 100 which are respectively fastened to and rotate with four radial horizontal shafts 21 mounted in bearings 22, two pairs of which are fastened to the under side of each beam 1 and 2.

The outer ends of the shafts 21 have re-

spectively fastened to them bevel pinions 23, which respectively mesh with four bevel gear wheels 24, respectively fastened to and rotatable with four vertical shafts 25, which 5 respectively extend through and are rotatable in four bearing tubes 26, respectively mounted a pair in each beam 1 and 2, and provided with flanges respectively at their lower ends which bear against the adjacent beams. The upper end of each tube 26 is threaded externally and has fitted on it a threaded collar 27 which bears on top of the adjacent beam.

Each shaft 25 has mounted on it and 15 tightly secured to it a collar 28 which is adapted to bear on the top of the adjacent collar 27.

Four ratchet wheels 29 are respectively fastened to and are rotatable with the shafts 20 25. Respectively oscillative on the shafts 25, above the ratchet wheels 29 are four levers 30, which extend respectively forwardly in front of and adjacent to the seats 3, Fig. 1.

25 Respectively engaging the ratchet wheels 29 and respectively pivoted to the under sides of the levers 30, are four pawls 31, which are respectively held engaged with the ratchet wheels 29 by springs 32 respectively fastened to the operating levers 30, Fig. 4.

Referring to the form of propelling mechanism shown in Figs. 1 to 4, the riders, occupying the seats 3, swing the levers 30 forwardly and draw them backwardly, as in rowing a boat. The pawls 31, on the backward movement of the levers 30 toward the riders in the adjacent seats, respectively engage the ratchet wheels 29, thereby revolving the vertical shafts 25 on their axes, and, through the intermediacy of the gear wheels 24, pinions 23, shafts 21, and pinions 20, effecting a revolving movement of the beams 1 and 2 in the direction indicated by the 40 arrows in Fig. 1, due to the traveling engagement of the pinions 20 with the fixed gear wheel 19.

Swinging the operating levers, as described, gives the operators of said levers 50 an exercise and sensation similar to that obtained in rowing a boat.

For safe guarding the riders and their clothes from being injured by the gears 24 and pinions 23, housings 33 respectively encircling these sets of gears may be fastened to the under sides of the beams 1 and 2, Fig. 3. A similar housing 34 may be fastened to the under side of the beam 2 so as to encircle the gear 19 and pinions 20, Figs. 60 2 and 3.

In the modification, shown in Figs. 5 to 8, the beams 1 and 2, seats 3 carried thereby, and the central support on which the beams revolve, correspond in construction 65 and mode of operation to the corresponding

parts shown in Figs. 1 to 4, the difference in construction of the modification residing in the propelling mechanism.

In Figs. 5 to 8 portions only of the beams 1 and 2 and only one seat 3 are shown. A 70 complete propelling unit embodying the modification is shown in these figures, of which the following is a description:

A vertical rock shaft 35 is oscillatively mounted in and extends through the carrying beam 2, and at its upper end is provided with a crank lever 36, which extends obliquely forwardly in front of the adjacent seat 3, carried at the right end of the beam 2.

Fastened to the lower end of the rock shaft 35 is a crank arm 37 to which is pivoted the outer end of a substantially radial horizontal bar 38, the inner end of which is provided with a pawl hook 39, which engages a ratchet wheel 40, which is fixed and fastened to the pipe 16 in the place occupied by the gear wheel 19 in Fig. 3, in the other form of my invention.

When the lever 36 is oscillated, the crank 90 arm 37 will reciprocate the bar 38 inwardly and outwardly.

When the rider pulls the crank lever 36 toward him, that is toward the adjacent seat 3, the bar 38 will move outwardly, thus causing the pawl hook 39 to engage a tooth of the ratchet wheel 40. As the ratchet wheel is fixed, the rider pulling on the crank lever 36, will cause the beam 2 to start a forward revolving movement. When the rider swings the crank lever 36 forwardly, the bar 38 will be moved longitudinally inwardly, thus causing the pawl hook 39 to slip over the ratchet teeth. When the lever 36 is again pulled rearwardly, the bar 38 will again move outwardly and the pawl hook 39 will engage another tooth of the ratchet wheel 40. If the rider continues to oscillate the crank lever 36, the beams 1 and 2 and parts carried thereby will revolve, and the pawl hook 39 will travel around the ratchet wheel 40.

The inner portion of the bar 38 is supported by a bracket 41 secured to the under side of the beam 2 and having a hole 42 through which the bar 38 extends and in which the bar is longitudinally slidably and laterally movable.

The pawl hook 39 is retained in operative engagement with the ratchet wheel 40 by means of a coil spring 43 one end of which is fastened to the bar 38 and the other end of which is fastened to an upright plate 44 fastened to and depending from the rear edge of the beam 2, Figs. 5 and 6, the bar 38 being disposed forwardly of said beam.

Two stop pins 45 and 46 may be mounted in the bar 38 at opposite sides of and adapted to respectively strike the bracket 41 for limiting the longitudinal movement of the bar 38 inwardly and outwardly, Fig. 7.

A collar 47 is fastened on the rock shaft 35 and rests on the beam 2 for supporting said shaft. A collar 48 is fastened to the rock shaft 35 below said beam 2 for holding the rock shaft from upward movement.

While I have shown but one complete unit of the modified form for propelling the beams 1 and 2, it is obvious that similar units may be similarly provided and disposed at both end portions of the beam 1 and at the other end portion of the beam 2. A portion of such a unit is shown mounted on the left portion of the beam 2.

I do not limit my invention to the structures shown and described, as other modifications, within the scope of the appended claims, may be made without departing from the spirit of my invention.

What I claim is:

1. In a merry go round, a central support, a device rotatable thereon having a radial beam carrying a seat, a fixed gear wheel mounted on said support, a vertical shaft, a horizontal radial shaft, bearing means supporting said shafts on said beam, driving gearing connecting said shafts, a pinion mounted on and rotatable with the horizontal shaft, and adapted for travel on and meshing with said fixed gear wheel, a ratchet wheel mounted on and rotatable with said vertical shaft, an operating lever oscillative

on said vertical shaft adjacent to said seat and adapted for oscillation by a person occupying said seat, and a pawl carried by said lever and engaging said ratchet wheel. 35

2. In a merry go round, two crossed beams adapted to serve as sweeps for carrying seats, a vertical bearing tube extending through said beams at their place of intersection and having an annular peripheral 40 flange bearing against the under side of the bottom beam, a collar on said tube bearing on the top of the upper beam, and fastening bolts extending through said beams and through said flange and said collar. 45

3. In a merry go round, two horizontal crossed beams adapted to serve as sweeps for carrying seats, a bearing tube extending vertically through said beams at their place of intersection and having an annular peripheral flange bearing against one of said beams, a collar on said tube bearing against the other beam, bolts extending through said beams and through said flange and said collar, a supporting spindle extending vertically into said tube, and bearing rollers carrying said tube and carried by said spindle. 50 55

In testimony whereof I have signed my name to this specification.

CLARENCE B. BURBRIDGE.
